CLAIM

I claim the ornamental design for the animal litter scoop, as shown.

DESCRIPTION

FIG. 1 is a perspective view of an animal litter scoop showing my new design;

FIG. 2 is a top plan view thereof;

FIG. 3 is a bottom plan view thereof;

FIG. 4 is a right side elevational view thereof, the left side being a mirror image of the right side shown;

FIG. 5 is a front elevational view thereof; and,

FIG. 6 is a rear elevational view thereof.
